UNITED STATES PATENT OFFICE

ALFRED L. RUTHVEN, OF ROCHESTER, NEW YORK

RUN-DOWN AND RESET TRAIN CONTROL

Application filed May 6, 1926. Serial No. 107,125.

The present invention relates to automatic train control apparatus, and aims to provide a novel and improved run-down and reset type of control apparatus which is operable to automatically retard or stop the vehicle or train after it has travelled a predetermined distance, unless the vehicle-carried control equipment has been reset automatically or manually.

10 It is also an object of the invention to provide an apparatus of the character indicated which is simple in construction and operation and which is also practical and efficient.

With the foregoing and other objects in view, which will be apparent as the description proceeds, the invention resides in the construction and arrangement of parts, as hereinafter described and claimed, it being understood that changes can be made within 20 the scope of what is claimed, without departing from the spirit of the invention.

The invention is illustrated in the accompanying drawings, wherein:—

Figure 1 is a diagrammatical view of one 25 form of apparatus embodying the improvements, for clear, caution and danger conditions, with provision for automatic resetting under trackside control.

Fig. 2 is a diagrammatical view of a simplified form of apparatus using trackside control for resetting the apparatus, and providing for two conditions of control only, such as clear and danger conditions.

Fig. 3 is a diagrammatical view of a still 35 more simple apparatus, employing a manually operable avoiding device, without control from the track to reset the apparatus.

Fig. 4 is a diagrammatical view of a pneumatic apparatus corresponding with the electrical apparatus as shown in Fig. 3.

Fig. 5 illustrates a portion of a track with a semaphore and an indicator or sign which indicate to the engineman the points along the track where the avoiding device should 45 be operated.

Fig. 6 is a diagrammatical view illustrating the trackside circuits for the apparatus shown in Fig. 1.

Fig. 7 is a diagrammatical view illustrating several blocks of a track with the sema-

phores and run-down indicator or sign, for the apparatus shown in Figs. 3 and 4.

Fig. 8 is a plan view of a pair of inductor bars and their supporting means located between the rails of a track.

Fig. 9 is an enlarged end view of the inductor bars and their supporting means as shown in Fig. 8.

Referring to Fig. 1, the vehicle-carried equipment includes a valve magnet 10, which 60 is an electromagnetically-controlled valve for opening the brake pipe of the vehicle or train to the atmosphere, when the magnet is deenergized, so as to apply the brakes and retard or stop the vehicle.

The valve magnet 10 is disposed in a normal running circuit including the electrical generator 11 or other source of electrical energy, conductor 12, shaft 13 of a speed control governor 14, conductor 15, magnet 10, conductor 16, run-down switch 17, contact strip 18 normally engaged by the switch 17, and return conductor 19. Thus, while the switch 17 engages the strip 18 such circuit is closed to keep the valve magnet 10 energized, and 70 should the shaft 13 of the governor 14 break, this will open such circuit so as to deenergize the magnet 10 and apply the brakes, thereby providing a safety feature.

A caution running circuit is provided to 80 enable the vehicle to proceed below a predetermined maximum caution speed, when the switch 17 moves open. Such circuit includes the generator 11, conductor 12, governor shaft 13, conductor 15, valve magnet 10, conductor 85 20, a caution run-down switch 22, contact strip 23 normally engaged by the switch 22, conductor 24, contact strip 25, switch or bridge 26 carried by the governor 14, contact strip 27, and conductor 19. In order that such 90 circuit may be closed to energize the magnet 10, the switch 22 must not only be closed, but the switch 26 must bridge the pair of contact strips 25, 27, which requires that the vehicle be moving at a speed below maximum caution speed, above which speed the switch 26 is removed from the strips 25, 27 to open the circuit and deenergize the magnet 10 so that the brakes will be applied.

A danger running circuit is provided to 100

enable the vehicle to proceed at a slow rate of speed under danger conditions, providing the engineman is alert. This circuit is employed when both of the switches 17 and 22 are open, in order that the vehicle may proceed under danger conditions below a maximum danger speed, permitting a quick stop to be made if necessary, and also enabling the train or vehicle to proceed to a point where repairs can be made or communication had with the train dispatcher. Such danger running circuit includes the generator 11, conductor 12, governor shaft 13, conductor 15, valve magnet 10, conductor 20, an alert switch 28 held closed by the engineman, contact 29, conductor 30, contact strip 31, bridging switch 32 carried by the governor 14, companion contact strip 33, and conductor 19. In order that such circuit may be closed, the switch 32 must bridge the pair of contact strips 31, 33, requiring that the vehicle be travelling at a slow rate of speed, and the engineman must also hold the switch 28 closed, said switch being normally open. This not only requires that the vehicle travel at a slow rate of speed, but the engineman must also be alert in holding the switch 28 closed. The switch 28 may also be used as an avoiding device to prevent the deenergization of the valve magnet 10 when travelling at a slow speed, with the switch 32 bridging the contact strips 31, 33, inasmuch as the engineman may close the switch 28 to keep the magnet 10 energized when the switches 17 and 22 are opened. The switches 26 and 32 which are carried by the governor 14 are swivelled to the rotary part of the governor, and are prevented from rotating by a guide 34. The switches 17 and 22 are arranged to run down in accordance with the distance of movement of the vehicle, so that said switches will be opened after the vehicle has travelled a predetermined distance. Thus, a helix 35 is provided, which, like the governor shaft 13, is geared or operably connected with one of the wheel axles of the vehicle, but the helix 35 rotates relatively slow while the governor rotates relatively fast. A slidable rod 36 is carried by each of the switches 17 and 22, to bear on the thread of the helix 35, whereby, as the helix rotates, the weighted long arms of the lever switches 17 and 22 will move downwardly by gravity, and when the rods 36 reach the lower end of the helix 35, the switches 17 and 22 will be removed from the respective contact strips 18 and 23, to open the normal and caution running circuits. Each rod 36 is projected by a suitable spring 37 to engage the helix 35, and a lever 38 is mounted on each switch and operably connects the rod 36 and the core 39 of a solenoid. There are two solenoids 40 and 41 controlling the switches 17 and 22, respectively, and said solenoids are normally deenergized, so that

the cores 39 will gravitate with the switches 17 and 22. When either of the solenoids is energized, it will attract and raise the corresponding core 39, thereby swinging the lever 38 to retract the rod 36 from the helix 35, and the switch is then swung upwardly to initial or starting position. Then, when the solenoid is deenergized the spring 37 will project the rod 36 into engagement with the helix 35 at the upper end thereof. This constitutes the resetting action, that is, the solenoid 40 or 41 is energized to retract the rod 36 from the helix and return or reset the corresponding switch to initial or starting position, as seen in Fig. 1. 70 75 80

A resetting circuit for the solenoid or electromagnet 40 includes the generator 11, conductor 12, governor shaft 13, conductor 15, solenoid 40, conductor 42, contact 43, switch 44, and conductor 19. A resetting circuit for the solenoid or electromagnet 41 includes the generator 11, conductor 12, governor shaft 13, conductor 15, solenoid 41, conductor 45, contact 46, switch 47, and conductor 19. 85

The resetting control switches 44 and 47 for clear and caution conditions, respectively, are normally open, and are under the control of the respective clear and caution electromagnets 48 and 49. Said electromagnets are controlled by the respective audion or thermionic tubes or valves 48' and 49'. Thus, the magnet 48 is connected in the circuit 50 with the battery or source of electrical energy 51 and the plate 52 and filament 53 of the thermionic valve 48', while the magnet 49 is connected in the electrical circuit 54 with the battery 51 and the plate 55 and filament 56 of the thermionic valve 49'. The construction and operation of the thermionic valves are well known and need not be described in detail. The circuits 50 and 54 are the output circuits of the thermionic valves 48' and 49', respectively, and the flow of electrical current in said circuits and magnets 48 and 49, respectively, is controlled by the flow of current in the respective input circuits 57 and 58 of the thermionic valves 48' and 49'. The circuit 57 is connected to the filament 53 and grid 59 of the valve 48', while the circuit 58 is connected to the filament 56 and grid 60 of the valve 49'. 90 95 100 105 110 115

The circuits 57 and 58 receive electrical energy by induction from the track, under clear and caution conditions, to obtain or maintain corresponding conditions in the vehicle equipment, and, each of the circuits 57 and 58 has a pick-up element to receive energy from the track. Thus, a pick-up coil 61 is disposed in the circuit 57, and a similar coil 62 is disposed in the circuit 58, said coils being wound on the respective cores 63 and 64. Said cores are of inverted U-shape as shown to be disposed astride the portions of the trackside circuits from which the coils receive their energy. 120 125 130

The coil 61 receives electrical energy by induction from one rail 65 of the track, and the coil 62 receives electrical energy by induction from an inductor bar or rail 66 mounted on the track at the control location. 5 The inductor bar 66 and corresponding portion of the rail 65 are energized electrically. Thus, a conductor 67 is connected to one end portion of the bar 66 and corresponding portion of the rail 65, and is connected to the control switches 68 and 69 for clear and caution conditions, respectively. The respective front contacts 70 and 71 of the switches 68 and 69 are connected by the conductors 72 and 73 with the rail 65 and bar 66 at the end of the bar 66 opposite to the end to which the conductor 67 is connected. The switches 68 and 69 are under the control of the respective clear and caution control electromagnets 74 and 75. These electromagnets are connected in the wayside signal circuits or are controlled in any suitable manner, according to the recognized practice, whereby when the track is clear ahead both magnets 74 and 75 will be energized to close the switches 68 and 69, when caution conditions exist in advance the magnet 74 is deenergized and the magnet 75 energized to open the switch 68 and close the switch 69, and when 20 danger conditions exist in advance both magnets are deenergized so that the switches 68 and 69 are both open. The trackside circuits are energized, as shown, by the provision of a transformer 76 between the conductor 67 and an alternating current supply line or circuit 77.

Fig. 1 illustrates the semaphore 78 in clear position, with the vehicle passing the control location. While the vehicle has been approaching the control location, the switches 40 17 and 22 have almost run down to open positions, said switches being in the act of moving away from the contact strips 18 and 23, respectively, Fig. 1 showing the run-down devices restored or reset.

The operation is as follows: Under clear track conditions ahead, the magnets 74 and 75 are energized to close the switches 68 and 69, whereby the inductor bar 66 and portion 50 of the rail 65 between the conductors 67 and 72 will be energized with alternating current of suitable voltage and phase. Then, as the coils 61 and 62 move over the energized portion of the rail 65 and the bar 66, respectively, alternating current will be induced in said coils, whereby the flow of current between the grids and filaments of the thermionic valves 48' and 49' will increase the flow of current from the battery 51 in the 55 circuits 50 and 54 to such an extent that the normally deenergized magnets 48 and 49 will be energized to raise the switches 44 and 47 against the respective front contacts 43 and 46. The switch 44 being closed will close the 60 resetting circuit of the solenoid 40, so that

solenoid 40 being energized will raise the switch 17 to initial position, as seen in Fig. 1. The switch 47 being closed will close the resetting circuit of the solenoid 41, so that the switch 22 is similarly raised to initial position. The coils 61 and 62 have a relatively long distance of movement over the bar 66 and energized portion of the rail 65, when passing the control location, to enable the switches 17 and 22 to be reset before the coils 70 leave the control location. The vehicle may therefore proceed under clear conditions inasmuch as both of the switches 17 and 22 have been reset, thereby permitting the vehicle to travel the predetermined distance 80 before the switches 17 and 22 reach the ends of the contact strips 18 and 23, respectively.

Under caution conditions, the magnet 74 is deenergized and the magnet 75 energized, so that the clear switch 68 is open and the caution switch 69 closed. The rail 65, therefore, does not receive energy, whereas the bar 66 is energized. Accordingly, the coil 61 will receive no energy from the track, while the coil 62 is energized. Consequently, the magnet 48 remains deenergized, while the magnet 49 is energized, thereby closing the switch 47 but leaving the switch 44 open. Consequently, the switch 17 is permitted to run down completely and open the circuit 90 thereof, said switch 17 being removed from the contact strip 18. However, the switch 47 being closed will energize the solenoid 41, when passing the control location, to reset the switch 22. The switch 17 being open 100 places the control of the valve magnet 10 on the switch 22 and governor switch 26, requiring that the vehicle travel below the predetermined maximum caution speed, with the switch 26 bridging the contact strips 25 and 27. The switch 22 being reset therefore enables the vehicle to proceed under caution speed for the predetermined distance of travel.

Under danger conditions, with both magnets 74 and 75 deenergized, and the switches 68 and 69 open, neither of the pick-up coils 61 and 62 receives energy from the track, so that the magnets 48 and 49 remain deenergized, with the switches 44 and 47 open. 110 Both switches 17 and 22 therefore run down to open position, and the control of the valve magnet 10 is now placed on the alert switch 28 and governor switch 32, requiring that the vehicle proceed at a slow speed and that the engineman be alert by holding the switch 28 closed. Should the vehicle exceed the maximum danger speed, the switch 32 being removed from the contact strips 31, 33 will open the circuit and deenergize the magnet 10, or 115 should the engineman be asleep, dead or otherwise incapacitated, the switch 28 being open will deenergize the valve magnet 10 and apply the brakes.

It will be apparent that if the vehicle is 120

proceeding under danger conditions and passes a control location under caution or clear conditions, the vehicle equipment will be reset accordingly, and if the vehicle is 5 proceeding under caution conditions and passes a control location under clear or danger conditions, the vehicle equipment will be controlled accordingly, so that the vehicle equipment may be controlled, at any control 10 location, for change from any one condition to either of the other conditions.

Fig. 2 illustrates a modification in that control for caution conditions has been eliminated, and the apparatus provides for a plain stop only if the run-down device is permitted to run down the full amount. This apparatus employs the valve magnet 10, run-down switch 17, solenoid 40, magnet 48, thermionic valve 48' and pick-up coil or receiver 51, the same as in Fig. 1, with the same corresponding circuits, and the portion of the rail 65 at the control location is energized by the same trackside circuit as shown in Fig. 1, under the control of the electromagnet 74 which is energized for clear conditions and deenergized for danger conditions. Said electromagnet 74 may also be deenergized for caution conditions, so that the vehicle will be stopped under either danger or caution conditions unless the engineman acknowledges the signal given by the semaphore 78 and avoids the de-energization of the valve magnet 10. When the magnet 74 is energized and the switch 68 closed, the coil 61 receiving energy from the rail 65, will result in the magnet 48 being energized and the switch 44 closed to energize the solenoid 40 and reset switch 17. When the rail 65 is deenergized at the control location, the magnet 48 and solenoid 40 remain deenergized, and the switch 17 will move to ultimate position so as to open the circuit of the valve magnet 10 and apply the brakes. The alert switch 28 is connected between the conductors 19 and 42, as shown, whereby the engineman, in approaching the semaphore, being alert may acknowledge the signal and thereby avoid the stopping of the vehicle. The switch 28 being closed will energize the solenoid 40 to reset the switch 17, the resetting circuit including the generator 11, conductor 12, solenoid 40, conductor 42, switch 28, contact 29, and conductor 19. If the engineman is dead, asleep or otherwise incapacitated, the switch 28 remaining open, with the switch 68 open, will result in the run-down device going to ultimate position and stopping the vehicle. The chief function of automatic train control is to cause obedience to wayside signals. Therefore, if the engineman is alert, the avoiding of the automatic stopping or retarding of the vehicle is not objectionable, inasmuch as the engineman being alert will manually control the vehicle or train according to the signal. The alert switch 28 is only to be closed when ap-

proaching or passing a control location, when the engineman observes the signal and controls the train accordingly. Therefore, if the engineman is dead, asleep or otherwise incapacitated, or if the signal is not observed because of fog or smoke, the alert or avoiding switch 28 will not be closed, and under caution or danger conditions the vehicle will be stopped automatically. The switch 28 may be of any suitable mechanical construction in order that it may not be tied or fastened in closed position, thereby requiring the switch to be held closed manually.

Fig. 3 illustrates a simple run-down and reset device with an alert switch, the valve magnet 10, switch 17, helix 35 and solenoid 40 being the same as shown in Figs. 1 and 2. There is no control from the track, but the engineman must be alert and acknowledge signals or indications at predetermined points of the track to avoid an automatic stop. The normal circuit of the valve magnet 10 includes the generator 11, conductor 12, magnet 10, conductor 16, switch 17, contact strip 18 and conductor 19. If the vehicle travels a predetermined distance so that the switch 17 is completely run down, the switch is removed from the contact strip 18, thereby de-energizing the magnet 10 and applying the brakes. The avoiding switch 28 is located between the solenoid 40 and conductor 19, so that the engineman, if alert, may acknowledge the wayside signals or indications, by closing the switch 28, which will energize the solenoid 40 and reset the switch 17, the circuit including the generator 11, conductor 12, solenoid 40, switch 28, contact 29, and conductor 19.

Fig. 4 illustrates a pneumatic apparatus to accomplish the same results as obtained by the electrical apparatus shown in Fig. 3. Thus, a valve 10' is provided for opening the brake pipe to the atmosphere, for applying the brakes, when said valve is opened. A run-down lever 17' has a rod 36' engaging the helix 35', so that when the lever 17' runs down the full amount, it will contact with the push button or plunger 10'' of the valve 10', thereby opening the valve and bleeding the air from the brake pipe to apply the brakes. This is the equivalent to the opening of the switch 17 hereinbefore described. The rod 36' is projected into engagement with the helix by the spring 37', and a lever 38' carried by the lever 17' operably connects the rod 36' with the stem of a piston 39' working in a cylinder 40'. Compressed air is supplied from the main reservoir 11' or other suitable source, and a valve 28' is connected between the reservoir 11' and cylinder 40'. The valve 28' is an alert valve operated similar to the switch 28 as shown in Fig. 3, for resetting the run-down device. Thus, by opening the valve 28', air is admitted from the reservoir 11' into cylinder 40' to raise the

piston 38' and restore the lever 17' as seen in Fig. 4. If the valve 28' is not operated before the lever 17' runs down completely, said lever 17' will open the valve 10' and thereby apply the brakes. The cylinder 40' preferably has vents 40'' and 40''' at its lower and upper ends. The vents 40'' permit the air to move into and out of the cylinder above the piston 39'. The vent 40''' permits the air to escape from below the piston 39' when the lever 17' gravitates, but said vent is not sufficiently large for the free discharge of air admitted into the cylinder from the reservoir 11' when the valve 28' is open, so that the piston 39' will be raised as above described.

Fig. 5 illustrates a portion of the track with a semaphore 78, and the rails of the track may have insulated joints in any suitable arrangement for the ordinary track circuits used in wayside signal systems. With the apparatus shown in Figs. 3 and 4 there are no control elements or circuits on the track, as seen in Fig. 5. The run-down devices are so geared to coact with the track mechanism disclosed in Fig. 5 that the vehicle travelling the length of an ordinary block from one semaphore to the next, will enable the run-down device to reach or approach ultimate vehicle retarding position, so that the vehicle will be retarded if the second semaphore is passed without the device being reset. If a block is of unusual length, an indicator or signal 79 of any suitable kind may be positioned at the side of the track between the ends of the block, to indicate to the engineer a point at which the avoiding or resetting device must be operated. These indicators or signs 79 may be used in the blocks at suitable points to indicate where the avoiding device should be operated, in addition to the signal locations where the semaphores are located.

Fig. 6 illustrates the trackside circuits for several blocks of the track, for the apparatus shown in Fig. 1. The semaphores 78^a, 78^b, 78^c and 78^d are located at the entrance ends of the respective blocks to the right of said semaphores. The semaphore 78^a is in clear position, so that the corresponding switches 68 and 69 are closed; the semaphore 78^b is in caution position, so that the switch 68 is open and the switch 69 closed; the semaphore 78^c is in danger position so that both switches 68 and 69 are open; and the semaphore 78^d is in caution position with the switch 68 open and the switch 69 closed. The block between the semaphores 78^c and 78^d is of greater length than the other block which may be of normal length or say two miles. In such longer block the run-down device would run down completely unless it were reset before reaching the control location. Therefore, in connection with the semaphore 78^d the trackside circuits are duplicated between the ends

of the long block. Thus, an inductor bar or rail 66^a is located between the ends of the block, and a bar or rail 66^b is located at the usual control location for the semaphore 78^d. The conductors 67, 72 and 73 have the respective branches 67^a, 72^a and 73^a, whereby the bars or rails 66^a and 66^b are simultaneously energized, as well as the corresponding portions of the rail 65. Thus, the same conditions of control are provided at the control location defined by the bar or rail 66^a as exist when approaching the semaphore 78^b.

Fig. 7 illustrates the same blocks and semaphores as in Fig. 6, for the apparatus shown in Figs. 3 and 4, there being no trackside circuits excepting the usual wayside signal circuits (not shown). The avoiding device is operated when approaching each of the semaphores, to reset the run-down device, and in the long block, an indicator or sign 79^d is located between the ends of the block, to indicate to the engineer a point where the avoiding device should be operated to reset the run-down device. These indicators or signs may be located at suitable points in long blocks for the resetting of the run-down device at the predetermined distance in advance of the next semaphores.

Figs. 8 and 9 illustrate supporting means for the inductor bars or conductors 66 of the trackside circuits. Thus, posts 81 are mounted on the ties or sleepers, and insulators 80 are mounted on said posts and have the bars 66 secured therein. The bars 66 are therefore insulated from the ground, to avoid the influence of stray electrical current.

Having thus described the invention, what is claimed as new is:—

1. Automatic vehicle control apparatus including a vehicle-carried run-down device for obtaining an ultimate vehicle retarding condition, and manually operable avoiding means for resetting said device, in combination with indicating means located at intervals along the path of movement of the vehicle to indicate points near and intermediate the ends of the blocks where the avoiding means should be operated to prevent said vehicle retarding condition.

2. Automatic vehicle control apparatus including a vehicle-carried run-down device operable in accordance with the movement of the vehicle to move to an ultimate position when the vehicle has travelled a predetermined distance, means operable when said device reaches said ultimate position for applying the brakes of the vehicle, and manually operable avoiding means controlling said device for resetting it, in combination with indicating means at intervals along the path of movement of the vehicle for indicating the points near and intermediate the ends of the blocks where the avoiding means

should be operated to prevent the application of the brakes.

3. Automatic vehicle control apparatus including two vehicle-carried run-down devices for obtaining ultimate vehicle retarding conditions, speed controlled means cooperable with one device to restrict the vehicle speed when the other device has run down, controlled trackside circuits including portions extending longitudinally of the track, and vehicle-carried means controlling said devices and including pick-up coils cooperable inductively with said portions of said circuits for resetting said devices selectively when said circuits are energized.

4. Automatic vehicle control apparatus including two vehicle-carried run-down devices for obtaining ultimate vehicle retarding conditions, speed controlled means cooperable with one device to restrict the vehicle speed when the other device has run down, controlled trackside circuits including portions extending longitudinally of the track, vehicle-carried means controlling said devices and including pick-up coils cooperable inductively with said portions of said circuits for resetting said devices selectively when said circuits are energized, and manually operable forestalling means cooperable with said speed controlled means and arranged to forestall the vehicle retarding conditions below a predetermined vehicle speed when both of said devices have run down.

5. Automatic vehicle control apparatus including two vehicle-carried run-down devices operable in accordance with the movement of the vehicle to reach an ultimate position when the vehicle has travelled a predetermined distance, vehicle retarding means controlled by said devices for obtaining vehicle retarding conditions when said devices have reached said ultimate position, speed controlled means cooperable with one of said devices for restricting the vehicle speed when the other device has reached its ultimate position, controlled trackside circuits each including a portion extending longitudinally of the track, vehicle-carried means controlling said devices and including pick-up coils cooperable inductively with said portions of the circuits for resetting said devices selectively when said circuits are energized, and a manually operable avoiding device cooperable with said speed controlled means and controlling the first named means to avoid the vehicle retarding conditions below a predetermined vehicle speed when both of said run-down devices have reached said ultimate position.

6. Automatic vehicle control apparatus including a vehicle-carried run-down device for obtaining an ultimate vehicle retarding condition, a trackside circuit including a portion of one of the traffic rails in said circuit and means for controlling the circuit, and vehicle-carried mechanism controlling said device

and including a pick-up coil cooperable inductively with said portion of the rail for resetting said device when said circuit is energized.

7. Automatic vehicle control apparatus including a vehicle-carried run-down device, means controlling said device for resetting same including a pick-up coil cooperable inductively with one rail of the track, and means for passing current through portions of said rail at predetermined points of the track to influence said pick-up coil and reset said device.

In testimony whereof I hereunto affix my signature.

ALFRED L. RUTHVEN.
